PAPER CUP

William Poster, Brooklyn, N. Y., assignor to Lily-Tulip Cup Corporation, New York, N. Y., a corporation of Delaware

Application January 9, 1940, Serial No. 313,051

2 Claims. (Cl. 229—1.5)

This invention relates to one-piece paper cups, formed from substantially circular blanks; the cups having pleated side walls tapered downwardly so that a quantity of them may be stacked or nested one within another for the purpose of storing or dispensing them from a machine.

More particularly, the invention relates to a novel structure of the upper or lip portion of the cups whereby that portion provides greater comfort and ease of drinking when engaged by the lips of the user. Furthermore, the novel structure is formed such as to render it very rigid even under unusual pressure.

An object of this invention is to produce an article possessing the foregoing desirable, useful and structural advantages while at the same time permitting of rapid and economical production methods in their manufacture.

This invention consists in the novel features, arrangements and combination of parts embodied by way of example in the article hereinafter described as illustrating a preferred form of the invention, and the invention will be more particularly pointed out in the appended claims.

Further objects, features and advantages of the invention will appear from the following specification and claims, taken in connection with the accompanying drawing, in which:

Fig. 1 is a perspective view of the cup; and

Fig. 2 is an enlarged cross-sectional view showing in more detail the upper or lip portion of the cup viewed along the line 2—2 of Fig. 1.

Referring to Fig. 1 of the drawing, the cup shown is formed from a circular disc of relatively thin paper of a character well understood by those skilled in the art. The disc is folded, by well-known mechanism, into cup form providing a substantially circular bottom 1 and pleated side wall 2. The pleats 3, commencing at the junction of the bottom and side wall, are longitudinally co-extensive with the side wall which extends upwardly with a slight outward inclination until it reaches the point indicated as 4. At this point the side wall 2 takes a relatively sharp outward flare forming a flange-like lip portion 5, which will be designated hereafter as the flange portion of the lip. This flange extends upwardly and outwardly from the point 4 and terminates in a pronounced bead or rolled edge 6.

As will be noted in Fig. 2, the rolled edge 6 is substantially circular in cross section and is offset a substantially equal distance from the upper and lower surfaces of the flange portion 5 so as to provide a substantial overhang of the respectively opposite sides of the roll 6 relative to the adjacent

surfaces of the flange 5. The roll 6 is formed by bending the pleated paper of the flange 5 sharply upward at the meridian 7; then curling the paper outwardly, downwardly, inwardly towards the lower surface of the flange, and then upwardly and inwardly so as to terminate interior of the bead.

While in the preferred form the cup is shown with a hollow in the center of the bead, it is not the intention to thus limit the invention, for a solidly rolled bead may be used with equal advantage. In short any method may be employed in forming a lip portion having substantially the same exterior contour as that of Fig. 2. Such a contour enables the user to grip the lip portion of the cup firmly and comfortably between his upper and lower lip, so that when the flange portion 5 (conveniently spaced outwardly from the main side wall) is pressed against the lower lip, the junction 4 of the side wall and flange will abut against the forwardmost tip of the lower lip while the rest of the flange, touching and overlying the upper surface of the lower lip, extends to the bead 6, which presses down upon the inner rim of the lower lip forming a seal between the cup and the lip. The portion of the bead offset above the upper surface of the flange 5 enables the upper lip of the user to grip the cup and, while holding it between the lips, press the lip portion down upon the lower lip to effect the above-mentioned seal formed by the under surface of the bead 6.

Furthermore, the outwardly flaring flange in combination with the particular formation of the bead provides improved rigidity at the lip of the cup and materially strengthens the cup side wall structure.

Having thus described my invention with particularity with reference to a preferred embodiment of the same, it will be obvious to those skilled in the art, after understanding my invention, that changes and modifications may be made therein without departing from the spirit and scope of the invention, and I aim in the appended claims to cover such changes and modifications as are within the scope of the invention.

the scope of the

1. A one-piece paper cup comprising a body having a bottom and a pleated side wall, said pleated side wall extending upwardly to and forming a lip portion, said lip portion comprising a flange projecting upwardly and outwardly away from the side wall about a circumferential line of fold, said flange at its outer end extending abruptly upwardly about a line of fold from

whence the pleated side wall after its said upward projection follows a circuitous path so as to provide a bead substantially circular in cross section and uniformly disposed with respect to the plane of the flange so as to have substantial portions of the bead located on either side of the plane of the flange lip.

2. A drinking cup having a paper body comprising a bottom, a side wall, and a lip portion terminating in a rolled paper bead, said lip por-

tion flaring outwardly away from the side wall so as to form an obtuse angle therewith and then extending sharply upwards so as to meet said bead substantially tangentially and provide the inner periphery thereof, said bead being substantially circular in cross section and having its cross sectional diameter disposed substantially in line with the outwardly flaring lip portion.

ESTATE OF WILLIAM POSTER.
